CLAIM

The ornamental design for a bag portion with a pigmented inner layer and a transparent outer layer with pattern, as shown and described.

DESCRIPTION

FIG. 1 is a front perspective view of a bag portion that includes a pigmented inner layer with pattern and a transparent outer layer with pattern;

FIG. 2 is an exploded view of the bag portion of FIG. 1 showing the pigmented inner layer with pattern and the transparent outer layer with pattern;

FIG. 3 is a close-up view of part of the transparent outer layer with pattern stacked on the pigmented inner layer with pattern;

FIG. 4 is a close-up view showing the pigmented inner layer with pattern;

FIG. 5 is a close-up view showing the transparent layer with pattern;

FIG. 6 is a cross-sectional view, taken along line 6-6, of the portion shown in FIG. 3;

FIG. 7 is a cross-sectional view, taken along line 7-7, of the portion shown in FIG. 4;

FIG. 8 is a cross-sectional view, taken along line 8-8, of the portion shown in FIG. 5;

FIG. 9 discloses the bag portion shown in FIG. 3 in a stretched configuration;

FIG. 10 discloses the bag portion shown in FIG. 4 in a stretched configuration; and,

FIG. 11 discloses the bag portion shown in FIG. 5 in a stretched configuration.

The broken lines in the drawings illustrate portions of the bag portion that form no part of the claimed design. The broken lines showing broken away portions illustrate the bag has no specific length. Where a dotted box is indicated, material inside the box is part of the claimed design.
